UNITED STATES PATENT OFFICE.

BASIL J. YANCHENKO, OF NEW YORK, N. Y., ASSIGNOR, BY MESNE ASSIGNMENTS, TO LIBERTY NATIONAL BANK, TRUSTEE, OF SYRACUSE, NEW YORK.

IRONING-PRESS BURN GUARD.

Application filed February 6, 1925. Serial No. 7,241.

This invention relates to ironing presses and more particularly to improvements in burnguard curtains to cover the exposed ironing surface of a high lifting head to protect the operator from the heat thereof when the press jaws are open.

An object of the invention is to produce improvements in ironing press burnguard curtains which are automatically operated by a combination gravity and power member thereby making it unnecessary to operate the curtain by attaching it to some moving part of the pressing machine. By way of example, the curtain is drawn across the ironing face by a gravity actuated means, as a weight, and moved away therefrom by power means as a wind-up spring.

Reference is had to the accompanying drawing for an understanding of the invention and it is to be noted that changes may be made without departing from the principle thereof because my invention covers means broadly for operating the curtain guard without depending on any mechanical connection with the press operating mechanism.

Figure 1 illustrates a fragmentary side view of an ironing press equipped with the improved burnguard curtain. In this view the press is closed and the curtain is withdrawn from between the jaws so as to permit the exposed hot metal face to approach the work and impart thereto a domestic gloss and finish.

Figure 2 shows a fragmentary side view of the press head in lifted or open position. In this view a gravity operated weight car has run down hill to draw the curtain across the exposed ironing face.

Figure 3 shows a detail sectional view of the curtain carrier which in this instance is a roller. The curtain carrier contains power means for winding up the curtain.

Figure 4 illustrates a plan view of the press head equipped with the burnguard curtain, and a portion of the curtain roller is shown in section to illustrate its exemplary construction.

Referring now more in particular to the drawings for a detailed description of the invention, there is shown a fragment of a pressing machine frame 10 which frame usually supports a press buck or jaw 11 and a swinging press lever 12 pivoted at 13 on the frame. The press lever 12 is actuated

by any suitable mechanism and is adapted to raise and lower a pressing head jaw 14. The pressing members or jaws 11 and 14 are usually heated by steam or any other suitable means, but the heating means as well as the operating mechanism for swinging the lever is not a part of the present invention and have therefore been omitted for brevity.

In laundry ironing machines, it is usually the practice to cover the lower pressing member, the buck 11, with a press cloth or pad while the upper press member, the head 14, has its exposed hot metallic ironing face 16 exposed so as to directly engage the laundered work or wash goods and impart thereto a domestic gloss. When the press is open with the head jaw 14 high above the buck 11, extended visibility of the buck 11 is afforded thereby enabling the operator to work between the open press jaws and spread the work out within the press. The operators are exposed to the heat radiated from the head, and besides the rapidity with which the operators work sometimes causes them to inadvertently touch the exposed ironing surface 16 which is unpleasant to say the least, and which sometimes burns the operator's hands. My improved gravity power closed and power return curtain guard eliminates all possible danger to the operator and thus affords more pleasant working conditions.

Each end of the head 14 may carry support brackets 18, a pair at each end, and a track or rod 19 is suspended on each pair of end brackets. A weight car 20 having car wheels 21 is mounted on the track 19 and adapted to travel back and forth thereon. The weight of the car 20 causes it to travel rearwardly from front to back of the press as the head lifts. This is due to the fact that the weight car 20 must run down hill as the head travels upwardly.

The forward brackets 18 support a curtain guard carrying member which, in the present instance, is shown as an ordinary roller 23. This roller 23 is journaled to rotate freely upon a shaft 24 which is fixed in the front brackets 18. A cloth curtain guard 25 is rolled upon the roller 23 with its inside edge anchored to the roller and the outside edge free to be drawn in and out relatively to the said carrier 23. The outer traveling curtain edge is attached to the

weight car 20 with the result that the car 20 unwinds the curtain 25 from the roller 23 when the head rises to Figure 2 position thereby quickly covering the ironing surface 16 by the cloth curtain guard which conceals the ironing surface from the operator thereby protecting him from the heat of the ironing face. The weight car 20 quickly travels rearwardly under the pull of gravity drawing the curtain 25 out as the head rises.

Power means are embodied in the roller for hauling the guard and car back to front normal position when the head is closed to 15 again uncover the ironing surface 16. To this end, the roller 23 is preferably provided with a spring chamber 27. A wind-up coil spring 28 is confined on the shaft 24 and one end of the spring is anchored to the roller 20 drum 23, as at 29, while the other end of the spring is anchored to the stationary shaft, as at 30. In this way, torque is stored in the power spring 28 when the curtain 25 is drawn outwardly, and this torque is sufficient to draw the curtain back as the head closes to return the track 19 to horizontal position since in that event the car rolls easily on level track.

It is desirable to provide adjustment 30 means to regulate the normal torque of the spring 28 when the roller is at rest which is to say that the spring 28 must be regulated as to its torque to suit the weight car 20. To this end, the shaft 24 is made with a 35 square end or nut head 31 on one end projecting from the bracket 18 in order that a wrench may be applied to the shaft 24 for winding up the spring 28. The stationary shaft 24 is provided with two or more holes 40 32 and a lock pin 33 is adapted to be inserted through the bracket and through the shaft 24 to lock the shaft in any desired position. In regulating the torque of the spring 28 to suit the weight car 20, the pin 45 33 is removed so as to free the shaft 24 in the journal brackets 18 whereupon the said shaft 24 is rotated a suitable number of times so as to partly wind up the spring 30 thereby building up sufficient power therein 50 as will rotate the roller drum 23 to wind the cloth guard 25 back on the roller when the press closes. Having adjusted the torque of the spring 28, the pin 33 is thrust back through the journal bracket 18 and shaft 24 55 to lock the shaft in fixed position.

In operation, the weight of the car 20 is sufficient to rapidly draw the curtain 25 across the ironing face 16 as the head goes up. The pull of the weight car 20 rotates 60 the roller drum 23 which winds up the spring 28 increasing the torque thereof. This is due to the fact that the track 19 is rapidly tilted to an angular position which gives the weight car 20 a down hill pull 65 against the spring 28.

As the head 14 is drawn downwardly towards the buck 11, the track 19 is returned to horizontal position thereby enabling the wound-up spring 28 to pull the weight car back to the front of the head which uncovers 70 the ironing face 16 just before the pressing machine closes upon the work.

It is to be noted that the operation of this ironing press burnguard is entirely independent of any moving part of the pressing machine and therefore the device is comparatively inexpensive and simple in its application to ironing presses.

What I claim is:

1. An ironing press comprising coacting 80 press jaws in combination, said jaws adapted to have a wide opening movement and one of the jaws being provided with an exposed metal ironing face, a guard member carried by the press, and gravity actuated mechanism to draw the guard across the exposed ironing face when the press opens.

2. An ironing press comprising coacting 90 press jaws in combination, said jaws adapted to have a wide opening movement and one of the jaws being provided with an exposed metal ironing face, a guard member carried by the press, gravity actuated mechanism to draw the guard across the exposed ironing face when the press opens, and means to draw the curtain away from the ironing face to expose it to the work as the press closes.

3. An ironing press comprising in combination, coacting press jaws, one of which opens high above the other to afford extended visibility of the work and having an exposed ironing face, a curtain guard holder carried by the opening jaw, a curtain carried by the holder and capable of being taken in and let out by the holder, power means adapted to draw the curtain in on the holder as the press closes thereby uncovering the ironing face, and gravity actuated means pulling the curtain out from the holder as the press opens to cover over the ironing surface while the press is open.

4. An ironing press comprising in combination, coacting press jaws, one of which opens high above the other to afford extended visibility of the work and having an exposed ironing face, a curtain guard holder carried by the opening jaw, a curtain carried by the holder and capable of being taken in and let out by the holder, a spring adapted to draw the curtain in on the holder as the press closes thereby uncovering the ironing face, and a weight pulling the curtain out from the holder as the press opens to cover over the ironing surface while the press is open.

5. An ironing press comprising in combination, coacting press jaws, one of which opens high above the other to afford extended visibility of the work and having an 130

exposed ironing face, a curtain guard holder carried by the opening jaw, a curtain carried by the holder and capable of being taken in and let out by the holder, a track carried by the opening jaw, a weight adapted to run on the track and attached to the curtain, said weight adapted to run down the track by gravity as the jaw lifts, and means to pull the weight back along the track as the jaw closes. 45

6. An ironing press comprising in combination, coacting press jaws, one of which opens high above the other to afford extended visibility of the work and having an exposed ironing face, a curtain guard holder carried by the opening jaw, a curtain carried by the holder and capable of being taken in and let out by the holder, a track carried by the opening jaw, a weight adapted to run on the track and attached to the curtain, said weight adapted to run down the track by gravity as the jaw lifts, and a spring adapted to be wound up by the movement of the weight running down the track 55 and unwinding to pull the weight back as the jaw closes. 60

7. An ironing press comprising in combination, a head provided with an exposed ironing surface adapted to coact with a buck and lift high thereabove, a track carried on the head and being inclined when the head is up and horizontal when the head is down, a weight car mounted on the track and running down hill as the head rises, a 65 burnguard curtain having one edge thereof attached to the weight car and the other edge anchored to the head, and means to pull the weight car back along the track when the head closes. 70

40 8. An ironing press comprising in combination, a head provided with an exposed ironing surface adapted to coact with a buck and lift high thereabove, a track carried on the head and being inclined when the head 75

is up and horizontal when the head is down, a weight car mounted on the track and running down hill as the head rises, a roller, a burnguard curtain carried on the roller and attached to the weight car, and means acting on the roller to roll the curtain thereon 80 as the head closes. 85

9. An ironing press comprising in combination, a head provided with an exposed ironing surface adapted to coact with a buck and lift high thereabove, a track carried on the head and being inclined when the head is up and horizontal when the head is down, a weight car mounted on the track and running down hill as the head rises, a roller, a burnguard curtain carried on the roller 90 and attached to the weight car, and a wind-up spring which is overcome by the pull of the weight car as the head rises but which draws the weight car back as the head closes. 95

10. A burnguard attachment for ironing presses comprising, a gravity operated member, a curtain attached thereto and spread out by the pulling force of the member, and power operated means receiving its energy from the gravity operated member to, 100 pull in the curtain. 105

11. A pressing machine comprising in combination, coacting opening and closing hot pressing jaws one of which has an exposed ironing face to engage the work, a 110 guard member carried on the press and adapted to cover the exposed face when the press is open, a weight connected to the guard to move it in one direction, a guide track on which the weight runs and said track tilting to an angular position as the press opens and tilting to a horizontal position as the press closes, and means to move the guard in the other direction. 115

In testimony whereof I affix my signature. 120
